UNITED STATES PATENT OFFICE

LEONARD H. COPPEL, OF LOS ANGELES, CALIFORNIA

SWIMMING APPLIANCE

Application filed July 27, 1931. Serial No. 553,387.

My invention relates to swimming and life saving appliances, and has for one of its objects the provision of a buoyant structure of such design and construction that it will 5 prove to be of great help to those receiving instruction in the art of swimming and which, when used by an experienced swimmer, will enable him to move through the water with increased speed and with an expenditure of 10 less exertion, thus preventing premature fatigue of the swimmer.

A further object of the invention is to provide a device of this character which will possess all of the desirable qualities of a life 15 preserver and which, in addition thereto, is so characterized that it may be comfortably worn by the user and which will not hinder free use of the arms and legs.

Another object of the invention is to provide 20 a swimmer's appliance which is of light weight and capable of being folded to assume a comparatively small and compact form when not in use.

A still further object of the invention is 25 to provide a device which may be satisfactorily employed as a beach cushion and which may be conveniently transported from place to place as desired.

In the drawings, 30 Figure 1 is a view showing the device applied;

Figure 2 is a view in elevation of the device;

Figure 3 is a section on line 3—3 of Figure 35 2;

Figure 4 is a section on line 4—4 of Figure 2;

Figure 5 is a section on line 5—5 of Figure 40 2;

Figure 6 is a view similar to Figure 2, showing a slightly modified form of the invention; and

Figure 7 is a section taken on line 7—7 of Figure 45 6.

In carrying the invention into practice, use is made of a structure which is preferably formed of rubber and provided with a circular neck-encircling portion 5 and an attenuated portion 6, the latter being of such length that it will extend from a point at the

neck of the user to a point approximately at the waistline, as clearly shown in Figure 1. Said structure, when formed of rubber, has its circular portion provided with an air chamber 6 and same directly communicates with an air chamber 8 which extends lengthwise of the attenuated portion 6. The free extremity of the portion 6 has its walls brought together and vulcanized one to the other so as to form a strong attaching tab 9, and, as illustrated, same has vertical slots 10 formed therein and so arranged that a waistline belt 11 may be passed therethrough, thereby affording a means of attachment of the structure to the body of the user. This 15 arrangement is also such that the circular portion 5 is maintained in a relatively fixed position with respect to the shoulders of the user, it being desired that the shoulders rest against said portion when the tab 9 is secured 20 to the belt as just mentioned. This construction is also desirable in order that the head of the swimmer may at the latter's option be slipped through the hole in the portion 5 and the entire device turned downward, after 25 which the ring portion may be placed under the buttocks of the swimmer in order that the swimmer may sit upon such portion and float upon the surface of the water. I have 30 shown the device applied to the person of the user with the attenuated portion 6 extending along the back of the user, but this is entirely optional and it should be understood that the position of the device may be reversed so as to bring the attenuated portion 6 in 35 front of the swimmer. In order that the attenuated portion 6 may adapt itself to the contour lines of the user at its point of application, it is desirable that such portion be wider at its base or free end than at any other point in the length thereof and that the sides of this portion be curved inwardly and then merge gradually, as at 12, into the peripheral surface of the ring portion 5. This also provides for an increase in the area 40 of the air chamber within the attenuated portion 6 at the point 13 thereof.

Connected with the free extremity of the attenuated portion 6 and leading to the air chamber thereof is a flexible inflating tube 100

- 14 by means of which air may be supplied to both the chamber of the attenuated portion 6 and the chamber of the ring portion. When the structure has been sufficiently inflated so as to give it the desired buoyancy, the flexible tube 14 may be folded upon itself and the folds thereof tied together by a rubber band, after which the tube may be tucked under the waistline belt 11.
- 10 In the modified form of the invention shown in Figures 6 and 7, the structure is preferably formed from a single length of rubber tubing and the structure is provided with an attenuated portion 15 similar to the portion 6 in the preferred embodiment and a ring portion 16 similar to the aforementioned portion 5. The attenuated portion 15 is formed by bringing two leads or branches 17, 17, of the tubing together and 20 lacing one to the other, as at 18. In order that this may be satisfactorily accomplished, strips of fabric 19 are vulcanized to the branches 17, 17, and same are formed with eyelets 20 through which a lacing 21 may be 25 trained. The free extremity of each of the portions 17 is formed with an attaching tab 22, and same is provided with vertical slots 23 for the accommodation therethrough of a waistline belt 24.
- 30 I do not wish to be limited to the construction of my device from rubber, as it obviously follows that same may be constructed of any other suitable well-known material and, in lieu of air, cork or similar material 35 may be employed to give the device the intended buoyancy.

Referring again to the preferred embodiment of the invention, it follows that when the same is deflated it may be folded into a 40 very compact package that can be conveniently carried upon the person of the user. It also follows that from the construction of the device same, when inflated, may be removed from the person of the user and employed as a beach cushion. In either example, 45 it should be borne in mind that the arms and legs of the user are at no time obstructed by any portion of the device.

I claim as my invention:

- 50 A swimming appliance comprising a buoyant structure formed with a neck-encircling portion and a single attenuated extension leading therefrom, and means for attaching the attenuated portion to the waistline of the 55 user, so as to permit the attenuated portion to extend either in an upward direction from the waistline with the neck-encircling portion positioned about the neck or in a downward direction from the waistline with the 60 ring portion under the buttocks of the user.
